SCREW MANDREL

Dale W. Keller, Oakdale Township, Washington County, Minn., assignor to Minnesota Mining and Manufacturing Company, St. Paul, Minn., a corporation of Delaware

Filed Aug. 6, 1968, Ser. No. 13,045

Term of patent 14 years

Int. Cl. D8—04

U.S. Cl. D8—267

FIG. 1

FIG. 4

FIG. 2

FIG. 3

FIG. 5

FIG. 6

FIG. 9

FIG. 7

FIG. 8

FIG. 10

FIG. 1 is a perspective view of the screw mandrel of the invention;

FIG. 2 is a front elevational view thereof, the rear being essentially a mirror image of the front;

FIG. 3 is a side elevational view thereof, the other side being essentially a mirror image;

FIG. 4 is a top plan view thereof;

FIG. 5 is a bottom plan view thereof;

FIG. 6 is a perspective view of another embodiment of the screw mandrel of the invention;

FIG. 7 is a front elevational view of the embodiment of FIG. 6, the rear being essentially a mirror image of the front;

FIG. 8 is a side elevational view of the embodiment of FIG. 6, the other side being essentially a mirror image;

FIG. 9 is a top plan view of the embodiment of FIG. 6;

FIG. 10 is a bottom plan view of the embodiment of FIG. 6.

I claim:

The ornamental design for a screw mandrel, substantially as shown and described.
